DESIGN FOR A RUG

Harold C. Strobel, Jersey City, N. J., assignor to Bigelow Sanford Carpet Co., Inc., a corporation of Massachusetts

Application November 22, 1934, Serial No. 54,110

Term of patent 7 years

To all whom it may concern:

Be it known that I, Harold C. Strobel, a citizen of the United States and resident of Jersey City, in Hudson County, and State of New Jersey, have invented a new, original, and ornamental Design for a Rug, of which the following is a specification, reference being had to the accompanying drawing, forming part thereof, in which a plan view of the rug is shown.

The drawing shows the complete rug.

The diagonal lines, circles and stippling represent contrasting colors, or contrasting tones of the same color.

I claim:

The ornamental design for a rug substantially as shown and described.

HAROLD C. STROBEL.
